To all whom it may concern:

Be it known that I, John J. Keal, a citizen of the United States of America, residing in Los Angeles, county of Los Angeles, and State of California, have invented a new, original, and ornamental Design for a Table, of which the following is a specification, reference being had to the accompanying drawing, forming part thereof.

Fig. 1 is a perspective view of a table, showing my new design.

Fig. 2 is a similar view of the table in another position with the leaf shown in Fig. 1 moved to elevated and forwardly projected position.

Fig. 3 is an enlarged cross-sectional view as taken on line 3—3 of Fig. 2 of the table as shown in Fig. 2.

Fig. 4 is a fragmentary rear view of the right half of the table as in Fig. 2.

I claim:

The ornamental design for a table, substantially as shown.
